RADIO APPARATUS

Albert Blain, Philadelphia, Pa., assignor to Radio Corporation of America, a corporation of Delaware

Application October 30, 1937, Serial No. 171,845

3 Claims. (Cl. 178—5.8)

This invention relates to radio apparatus and has special reference to the provision of improvements in television receivers.

The prior art is replete with television receivers of various construction and design. Thus, it has previously been proposed to provide a cabinet wherein the image produced on the screen of a vertically mounted image tube is viewed in a mirror contained in a movable lid with which the cabinet is provided, the loudspeaker being mounted at the front of the cabinet. Another receiver has the image tube mounted in a horizontal position adjacent the top of the cabinet, while the loudspeaker is mounted adjacent the base, near the floor. Irrespective of the advantages claimed for these different constructions, it may be said generally that they are objectionable in that the music or speech accompanying the image emanates from a point remote from the image, so that the effect produced upon the audience is less realistic than that achieved, for example, in the talking moving-picture art.

Accordingly, a principal object of the present invention is to provide a television receiver wherein in the sound which accompanies the image appears to emanate from the image.

Another and related object of the invention is to provide a novel tuning control mechanism which permits the tuner itself to be mounted at a remote point and the loudspeaker to be mounted adjacent the image tube in the space usually allotted to the main tuning condenser and its associated parts.

Other objects and advantages, together with certain details of construction, will be apparent and the invention itself will be best understood by reference to the following specification and to the accompanying drawings, wherein:

Figure 1 is a front plan view of a television receiver having the parts designed, positioned and arranged in accordance with the principle of the invention.

Figure 2 is a front elevational view, and

Figure 3 is an end view of a condenser drive mechanism which is preferably employed in carrying the invention into effect.

Figure 4 is a fragmentary view in perspective, and

Figure 5 is an exploded view showing certain details of construction of the tuning mechanism more generally shown in Figs. 1 to 3, inclusive.

In Fig. 1, P designates generally the front panel of a television cabinet having a central axis indicated by the broken lines x—x. A chassis B 55 for the electrical apparatus is mounted within

the cabinet. Panel P is provided with three cut-away areas along axis x—x to provide (a) an aperture A in which the screen of a kinescope or other image tube K is framed, (b) an aperture A' for a tuning scale D, and (c) an opening A² through which sound from a loudspeaker LS passes and adjacent the top of which a tuning control shaft S is accommodated. As indicated in the drawings, the geometrical center of each of the parts K, D, S, and LS falls along, or is in register with, the central axis x—x. It will be noted that the loudspeaker LS is here separated from the image tube merely by the panel area necessary to accommodate the tuning scale D. The result is that sound from the speaker seems, to a nearby audience, as if it, in fact, emanated from the image. This desired impression is rendered possible because the cumbersome tuning condenser C is not interposed between the image and sound areas, but is mounted to one side of, and remote from the axis x—x.

It might appear that the aural illusion above discussed might be more complete if the scale or dial D were likewise removed to one side or the other of the axis x—x and the loudspeaker placed still closer to the image tube. The advantage thus gained, however, is very slight and is more than off-set by the sacrifice of symmetry in the appearance of the cabinet; further, it is desirable that the dial, the image and the tuning knob be centrally arranged so that the operator may ascertain (a) the tuning adjustment and (b) the image adjustment at a single glance.

The principal difficulty encountered in carrying the inventive concept of the instant case into effect was the provision of means ensuring an accurate indication of the angular position, or station frequency, to which the main tuning condenser is adjusted. Considered from another aspect, the problem was to provide a condenser driving mechanism, the operation of which would be characterized by freedom from such "back lash" as would ordinarily arise (a) at the point where the driving force is transferred to the coupling which necessarily extends from the tuning control shaft to the main tuning shaft, and (b) at the point where the driving force is transferred from the coupling to the condenser shaft or its gear.

A mechanism which obviates the above described and other difficulties incident to the control of a remotely disposed tuning device is shown in Figs. 2 to 5, inclusive. In these drawings B designates the chassis above which the main tuning shaft (see Fig. 3) of the set is conveniently 55

mounted. Suitably coupled to shaft 1 as by a rubber spider 2 is a stub shaft 3 which is journaled in a bushing 4 which, in turn, is supported by an upright extension 5 on an immovable bracket 6. A gear sector 7 fixed to the stub shaft as by a set screw 8 extends slightly beyond the front plane of the bracket. This bracket 6 is immovably fixed to the chassis B by a pair of arms or flanges 9 which are anchored to the chassis top as by bolts 10.

The immovable bracket 6 is provided with two grooved lugs 11^a, 11^b which extend outwardly from its front surface. These grooved lugs support a slotted rack 12. The edge of one of the slots 12^a in the rack fits in the groove of lug 11^a and the edge of the other slot 12^b fits in the groove of the other lug 11^b. Cut away portions 12^c and 12^d which communicate with the slots 12^a, 12^b, respectively, and permit the rack 20 to be seated in the grooves of the lugs 11.

An end section 13 of the upper surface of the rack 12 is provided with teeth 13^t which mesh with the teeth on the gear 7 which drives the stub shaft 3. An opposite lower end section 14 of rack 12 is also provided with teeth 14^t. The lower teeth 14^t mesh with a pinion 15 on the inner end of the centrally disposed tuning control shaft S. Shaft S is journaled in a bushing 16 which is fixed as by spacers 17 and screws 30 18 to a dependent portion of the mounting bracket 6.

When the knob N on the end of the control shaft S is turned, the pinion 15 will move the rack 12; when the rack 12 moves, the gear 7 on shaft 3 is rotated because its teeth mesh with the teeth 13^t on the upper end section 13 of the rack. Since the stub shaft 3 is coupled (by the spider 2) to the main tuning shaft 1, the angular setting and hence the frequency of the tuner 40 may be adjusted as determined by the degree of rotation imparted to the tuning knob N.

Unless some "take-up" device is provided adjacent the point at which the pinion 15 meshes with the rack teeth 14^a and adjacent the point at 45 which the gear 7 meshes with the rack teeth 13^t, the main tuning shaft 3 will not move in perfect synchronism with the control shaft S. To prevent such "lag" or "back lash" two auxiliary toothed rack elements 19 and 20 are affixed, respectively, to the upper (13) and lower (14) toothed end sections of the rack 12 as by means of take-up springs 19^a, 19^b and 20^a, 20^b, respectively. These take-up springs are accommodated in small slots which are provided for that 55 purpose adjacent the opposite ends of each of the paired toothed rack sections (13 and 19, 14 and 20) and permit of a limited range of movement therebetween. Thus, 19 may be moved with respect to 13, and 20 may be moved with respect to 14, so that in assembling the device the teeth 19^t and 13^t bear on opposite flanks of the teeth on gear 7, and teeth 14^t and 20^t bear on the opposite flanks of the teeth of the pinion 15. There is thus no lost motion in transmitting 65 torque between the tuning control shaft S and the condenser shaft 3.

A distinctive indication of the station (or frequency) to which the set is tuned is provided by an arrangement similar to that disclosed by the 70 same inventor in United States Patent No. 2,084,182. Adapted to the instant case, the tun-

ing indicator therein described comprises a translucent colored scale D, a differently colored transparent mask M, and a source of light L. Lamp L is shown mounted on the top of the chassis B; the transparent mask M is supported by a pair 5 of upwardly extending arms 21 on the immovable bracket 6 and the scale D is secured to a frame 22 which extends outwardly from and moves with the rack 6. The arms 21 which support the colored transparent mask M are provided at their upper ends with guide-pins 21^a-21^b, which maintain the moving translucent scale D in close proximity thereto. As described in the above identified patent, the scale markings D' have a better light transmitting 15 characteristic than the surrounding portion of the scale and the translucent mask M is provided with a slot M' of a suitable contour so that a bright spot of light is superimposed upon each of the scale markings as the receiver is tuned 20 throughout its tuning range.

Certain modifications of the invention will suggest themselves to those skilled in the art. It is to be understood, therefore, that the foregoing is to be interpreted as illustrative and not in a 25 limiting sense, except as required by the prior art and by the spirit of the appended claims.

What is claimed is:

1. A television receiver comprising an image tube, a tuning control shaft and a loudspeaker 30 mounted in closely spaced relation along a common axis, a tuner and a tuning shaft therefor mounted remote from said tuning control shaft and said axis, a driving gear on said control shaft, a driven gear on said tuning shaft, a rack 35 having discrete toothed sections which mesh respectively with said gears, and means individual to said discrete toothed rack sections for maintaining the teeth of each of said sections in intimate contact with the gear adjacent thereto. 40

2. A television receiver comprising an image tube, a tuning control shaft and a loudspeaker mounted in closely spaced relation along a common axis, a tuner having a tuning shaft mounted substantially parallel to and remote from said tuning control shaft, a driving gear on said control shaft, a driven gear on said tuning shaft, a rack having discrete toothed sections which mesh respectively with said gears, and means comprising a separate toothed member mounted 50 on said rack closely adjacent said sections and relatively movable with respect thereto for maintaining said rack in energy transfer relation with said driving and driven gears. 55

3. A television receiver comprising an image tube, a tuning control shaft, and a loudspeaker mounted in closely spaced relation along a common axis, a tuner and a tuning shaft mounted substantially parallel to and remote from said tuning control shaft, a driving gear on said control shaft, a driven gear on said tuning shaft, a tooth rack for transmitting a driving force between said control and tuning shafts, a pair of auxiliary toothed sections mounted to permit independent relative movement on said rack and positioned to mesh respectively with said gears, and means for separately biasing said relatively movable auxiliary rack sections whereby to maintain the teeth thereon in mesh with said gears. 60
